FORGING APPARATUS

Charles Fassinger, Pittsburgh, Pa.

Application July 23, 1935, Serial No. 32,739

17 Claims.

(Cl. 10—78)

My invention relates to forging apparatus, and is hereinafter described as employed in the hot-forging of nut blanks and the like, but it will be understood that various features of the invention can be employed in the forging and punching of other articles.

The invention is primarily concerned with forging operations wherein blanks are punched or pierced by a punching tool movable through the blank, the piercing tool being opposed by a supporting tool at the opposite side of the blank during partial piercing of the blank, thereby causing swelling of the blank, the supporting tool being then withdrawn and the punching tool being moved entirely through the blank to complete the piercing operation and eject the slug thus formed.

One object of my invention is to provide means for effecting properly-timed relation as between the movements of a punching tool and an opposed supporting tool, whereby they will properly cooperate to effect swelling and piercing of the blank, and whereby adjustments can be readily made during operation of the apparatus to maintain proper cooperative relation even after wear and looseness occurs in the operating parts of the machine.

Another object of my invention is to provide mechanism for co-relating or synchronizing the operation of opposed tools, whereby the relative thickness or volume of nut blank and slug can be controlled to effect production of nut blanks of uniform characteristics, irrespective of variation in the bar stock.

A further object of my invention is to provide a forging and punching machine of generally simplified form and improved operating characteristics.

In the accompanying drawings, Figure 1 is a side elevational view of the machine; Fig. 2 is a plan view thereof; Fig. 3 is an enlarged view taken on the line III—III of Fig. 2; Fig. 4 is a plan view of the structure of Fig. 3; Fig. 5 is a view, on an enlarged scale, taken on the line V—V of Fig. 3; Fig. 6 is an enlarged view showing one stage of the blank-piercing and swelling operation, and Fig. 7 shows another stage of said operation.

The machine is shown as provided with a suitable framework 8 and a main shaft 9 journaled therein. The shaft 9 is driven from a suitable source of power, through pulleys 10, and carries a pinion 11 which has driving engagement with gear wheels 12 and 13, that are mounted on shafts 14 and 15, respectively. The shaft

14 is supplied with a crank 16 that serves to reciprocate a cut-off slide 17 that has a combined cut-off tool and pressing die 18 which, when the slide is advanced, will shear a blank 19 from the forward end of a bar. The bar stock will be positioned in front of the cavity of a die 20, so that when the cut-off tool 18 is advanced to the die cavity it will shear a blank from the end of the bar stock and push it into the die. The die 20 is mounted in a stationary block 21.

During the shearing operation, a crowning tool 22 occupies a stationary position within the die 20. A piercer or punch 23 is slidably mounted within the crowning tool 22. During advancing movement of the cut-off tool 18, the piercing tool 23 is advanced to partially pierce the blank as shown more clearly in Fig. 6, and to finally eject the punch or slug.

The crowner tool 22 is mounted on a slide 24 and the piercer 23 on a slide 25, the slides 24 and 25 being operated by cams 26 and a single cam 27, respectively, that are secured to the shaft 15. The cams 26 and 27 are offset relative to one another so that the crowner tool 22 is stationary during the initial movement of the piercer 23 into the die, and thereafter advances more slowly than the piercer.

The slide 24 is yieldably held against the working face of the cams 26 by a lever 28 and a spring 29, while the slide 25 is moved against the face 30 of its cam 27 by a retracting cam 30 which is mounted on the shaft 15. Considerable force is required to withdraw the piercing die from the blank, and therefore the cam 30 is provided for positively withdrawing or stripping the piercer 35 from the blank. An abutment screw 31 is provided for the crowner slide 24 for adjustably positioning the crowner 22 in the cavity of the die 20 for making nuts of various thicknesses. The position of the piercer 23 within the crowner 22 is controlled by an adjusting screw 32.

Reciprocably mounted within the cut-off tool or presser 18 is a blank-supporting tool or filler pin 35 disposed opposite to and in axial alignment with the piercer 23. The supporting tool 45 is actuated by a slide block 36 that is operated by toggle links 37, whose rear ends are pivotally connected to the slide 17, and whose forward ends are pivotally connected to the block 36. A link 38 is connected to the mid portion of the toggles 37 and to a rocking lever 39 that is journaled at its mid portion upon the slide 17.

A screw-like adjusting element 42 is carried by the slide 17 beneath the mid portion of the toggles, for limiting the distance which the links 37

may move downwardly past center. Normally, the toggle is set with the links 37 substantially in parallelism, or slightly below center, whereby the forward end of the supporting tool 35 is maintained substantially flush with the working face of the presser 18. With the supporting tool 35 in this position, it opposes the piercer 23 and supports the central portion, while the presser tool supports the peripheral portion of the side 10 face of the blank.

Thus, at the time the piercer is moving into the blank, the supporting tool 35 is engaging the other face of the blank and opposes axial flow of metal in front thereof, and the metal is caused 15 to flow radially, thereby expanding the blank and filling out the die cavity, as shown in Fig. 6.

The supporting pin 35 is not positively connected with the slide block 36, but reciprocates within the bore of the presser tool 18. The block 20 36 is provided with a bore 40 to the rear of the tool 35, across which a plate 41 is positioned. With the toggle 37 in set position, the plate 41 engages the rear end of the tool and pushes it forwardly and maintains it in position flush with 25 the face of the presser tool 18. In case there is excessive pressure developed during piercing of a blank, as by excessive thickness of the bar stock or by failure of a previously-formed blank to be removed, the plate 41 is punctured or 30 sheared, permitting rearward movement of the supporting tool and relieving the opposition to the piercer so that no radial flow of metal occurs. The provision of the breaker plate 41 prevents possible serious damage to the machine under 35 excessive pressures.

After the piercer 23 has penetrated the blank a predetermined distance, with axial flow of metal opposed by the supporting tool 35, thereby causing expansion of the blank, as heretofore 40 described, the opposing pressure of the tool 35 must be removed, to permit completion of the piercing operation. Forward movement of the slide 17 carries the lever 39 forwardly and its front end moves under a tripper bar or rocking 45 cam 44, mounted on a shaft 45 which is journaled on the block 21. A crank arm 46 is mounted on the shaft 45 and a link 47 is pivotally connected thereto.

A turn-buckle type adjusting member 48 has 50 screw-threaded connection with the link 47, and is likewise connected to one end of a pull rod 49. The other end of the pull rod 49 is pivotally connected to one arm of a bell crank lever 50 that is journaled to the frame 8. The other 55 arm of the bell crank carries a roller 51 which engages a cam 52 mounted on the cam shaft 15.

The cam 52, operating through the connections above described, moves the tripper bar 44 downwardly into engagement with the lever 39. Consequently tilting of the lever 39 quickly moves the links 37 to their uppermost positions, as indicated in Fig. 3, and thereby moves the slide block 36 rearwardly which releases and permits rearward movement of the supporting tool 35 under 60 continued movement of the piercer 23.

The operation of the supporting tool 35 must be in definitely-timed relation to the movement of the punch 23, and this synchronism is effected by oscillating the tripper bar 44 from the cam shaft 70 15, by the cam 52, which is an important feature of my invention, since the cam 52 and the piercer cam 27 are in effect, an integral unit, there is no lost-motion or back lash of the parts to affect the timing relation, such as would be 75 present in case the pin in the presser would be

actuated through means on the cam shaft 14, for example. Also, the timing relation is unaffected by looseness and wear of the machine.

The movements of the piercer 23 and the presser 18 and its pin 35 are such that when these 5 members reach the position shown in Fig. 6, the pin 35 is immediately released as above-explained, and the movement of the piercer 23 is continued to push the slug of metal 53 from the blank and into the presser tool 18, the pin 35 10 being moved rearwardly thereby, thus completing the piercing operation of the blank. When the piercer 23 is at approximately the end of its advancing movement through the blank, the presser or cut-off tool 18 is completing its advancing 15 stroke to push the blank against the crowning tool 22, to thereby compress the blank within the die 20, to effect a crowning operation thereon. It will be understood, of course, that the front face 20 of the tool 22 could be plane in order to produce a flat-ended blank.

The advancing and retractive movements of the tool 35 through operation of the toggle links 37 takes place during continuous advancing movement of the cut-off 18, and during advancing movement of the piercer 23.

Upon completion of the piercing and crowning operation, the cut-off tool 18 is withdrawn from the die 20, while the advancing movement of the crowning tool 22 is continued to push the blank 30 19 from the die. To restore the toggle links 37 from their upper position to the position shown in Fig. 3, the rear end of the lever 39 is brought into engagement with a reset bar 54 during retractive movement of the slide 17. This movement causes the slug 53 to be ejected from the 35 presser 18.

During the forward movement of the crowning tool 22, the cam 30 will cause withdrawal of the piercer 23 to strip it from the blank 19, and to 40 bring it to its retracted position, and after ejection of the blank from the die, the spring 29 will withdraw the crowning tool 22 to its rear position.

It is, of course, highly important that there be 45 properly-timed relation between movements of the piercer 23 and the presser 18, and tripping of the toggle 37 to move the slide 36 away from the tool 35, such timing being effected as above-explained by the tripper bar 44, and the movement thereof from the cam shaft 15. In order that the tripper 44 can be adjusted to cause operation of the toggle links 37 at exactly the proper stage of forward movement of the piercer 23 and the presser 18, the adjusting member 48 is turned 50 which results in raising or lowering of the tripper bar 44 relative to the forward end of the lever 39, so that breaking of the toggle and release of the supporting tool or pin 35 will occur at precisely the desired stage in advancing movement of the piercer 23 and the presser 18, thus 55 insuring release of the pin 35, without interference with the continued advancing movement of the piercer 23 and the presser 18.

This toggle and cam arrangement for operating the slugger 35 constitutes an important feature of the present invention, since the tripping block 44 can readily be adjusted by the member 48 to compensate for wear and looseness in other parts of the mechanism.

Also, the timing of the release of the pin 35 can be readily changed to suit blanks of various thicknesses. The snap-like positive movement of the slugger is of importance because there is less danger of interference with the advancing 75

movement of the piercer. Furthermore, the release of the pin 35 can be effected in such timed relation to the movement of the piercer that the relative volumes of the nut blank and the remaining slug can be controlled to effect displacement and flow of metal from the slug to the blank to produce nut blanks of uniform size and thickness characteristics. That is, the thickness of the slug need not be uniform, but more or less metal therefrom, as required, is displaced into the body of the nut blank, so that the blanks are uniform. This effects considerable savings in scrap metal and scrap nut blanks.

I claim as my invention:

1. Forging apparatus comprising a blank-receiving die having openings in opposite sides thereof, a tubular pressing tool movable into one side of the die, a tubular crowning tool movable into the other side of the die, a pin reciprocable mounted in the pressing tool, means for holding said pin with its one end substantially flush with the adjacent end of the pressing tool, a piercing punch in the crowning tool, means for advancing said punch beyond the end of the crowning tool,

means for releasing the said pin, for movement rearwardly of the presser tool, means for thereafter continuing the advancing movement of the piercing punch, and means controlled through movement of the piercing punch, for effecting release of said pin.

2. Forging apparatus comprising a blank-receiving die having openings in opposite sides thereof, a tubular pressing tool movable into one side of the die, a tubular crowning tool movable into the other side of the die, a pin reciprocable in the pressing tool, a piercing punch in the crowning tool, said pin and said punch being disposed in axial alignment, means for advancing the piercing punch beyond the end of the crowning tool, means operable during advancing movement of the pressing tool for holding the said pin in position with its forward end substantially flush with the face of the pressing tool, and means for actuating said holding means, to release said pin.

3. Forging apparatus comprising a blank-receiving die having openings in opposite sides thereof, a tubular pressing tool movable into one side of the die, a tubular crowning tool movable into the other side of the die, a pin reciprocable in the pressing tool, a piercing punch in the crowning tool, said pin and said punch being disposed in axial alignment, means for advancing the piercing punch beyond the end of the crowning tool, means operable during advancing movement of the pressing tool for holding the said pin in position with its forward end substantially flush with the face of the pressing tool, and means for actuating said holding means, to release said pin, the said actuating means being adjustable for operation of the said holding means at a desired stage in the advancing movement of the pressing tool.

4. Forging apparatus comprising a blank-receiving die having openings in opposite sides thereof, a tubular pressing tool movable into one side of the die, a tubular crowning tool movable into the other side of the die, a pin reciprocable in the pressing tool, a piercing punch in the crowning tool, said pin and said punch being disposed in axial alignment, means for advancing the piercing punch beyond the end of the crowning tool, a toggle having a pair of links arranged substantially in parallelism, for maintaining the forward ends of said pin and said pressing tool

substantially in a common plane, and a tripping device operable during advancing movement of the pressing tool, for moving the said links out of their parallel position, to release said pin.

5. Forging apparatus comprising a blank-receiving die having openings in opposite sides thereof, a tubular pressing tool movable into one side of the die, a tubular crowning tool movable into the other side of the die, a pin reciprocable in the pressing tool, a piercing punch in the crowning tool, said pin and said punch being disposed in axial alignment, means for advancing the piercing punch beyond the end of the crowning tool, a toggle having a pair of links arranged substantially in parallelism, for maintaining the forward ends of said pin and said pressing tool substantially in a common plane, a lever connected to the mid-portion of said toggle, a tripper bar disposed adjacent to the path of travel of said presser tool and said lever, and means actuated by said punch-advancing means for operating said tripper, to break said toggle.

6. Forging apparatus comprising a blank-receiving die having openings in opposite sides thereof, a tubular pressing tool movable into one side of the die, a tubular crowning tool movable into the other side of the die, a pin reciprocable in the pressing tool, a piercing punch in the crowning tool, said pin and said punch being disposed in axial alignment, means for advancing the piercing punch beyond the end of the crowning tool, a toggle having a pair of links arranged substantially in parallelism, for maintaining the forward ends of said pin and said pressing tool substantially in a common plane, a lever connected to the mid-portion of said toggle, a tripper bar disposed adjacent to the path of travel of said presser tool and said lever, and means actuated by said punch-advancing means for operating said tripper, to break said toggle, said tripper bar being disposed in position to overlie said lever.

7. Forging apparatus comprising a blank-receiving die having openings in opposite sides thereof, a slide member, a blank-engaging pin carried thereby and movable into one side of the die, means on the slide for projecting the said pin forwardly of the slide, a piercing punch movable into the other side of the die, means for simultaneously advancing the piercing punch and the slide, and means operable during said advance movements for actuating said projecting means to release said pin from its projected position, and permitting retracting movement of the same during continued advance movement of the piercing punch.

8. Forging apparatus comprising a blank-receiving die having openings in opposite sides thereof, a slide member, a blank-engaging pin carried thereby and movable into one side of the die, means on the slide for projecting the said pin forwardly of the slide, a piercing punch movable into the other side of the die, means for simultaneously advancing the piercing punch and the slide, means operable during said advance movements for actuating said projecting means to release said pin and permitting retracting movement of the same during continued advance movement of the piercing punch, and a controlling device for said actuating means, actuated through advance movement of the piercing punch.

9. Forging apparatus comprising a blank-receiving die having openings in opposite sides thereof, a slide member, a blank-engaging pin carried thereby, a piercing punch movable into

the other side of the die, means for simultaneously advancing the piercing punch and the slide, toggle mechanism between one end of said pin and the slide and arranged to project the pin forwardly of the slide, for movement into the slide, and means adjacent to the path of travel of the slide for actuating said toggle mechanism to withdraw the same and permit retraction of the said pin during further advancing movement of the slide member and said piercing punch.

10. Forging apparatus comprising a blank-receiving die having openings in opposite sides thereof, a slide member, a blank-engaging pin carried thereby, a piercing punch movable into the other side of the die, means for simultaneously advancing the piercing punch and the slide, toggle mechanism between one end of said pin and the slide and arranged to project the pin forwardly of the slide, for movement into the slide, and means adjacent to the path of travel of the slide for actuating said toggle mechanism to withdraw the same and permit retraction of the said pin during further advancing movement of the slide member and said piercing punch, the toggle mechanism comprising a pair of links arranged substantially in parallelism, for projecting said pin, said links being moved out of parallelism when the toggle mechanism is actuated, and means operable upon retractive movement of the slide to restore the toggle links to their original parallel position.

11. Forging apparatus comprising a blank-receiving die having openings in opposite sides thereof, a blank-engaging tool, a piercing punch, means for moving the piercing punch through the die, means for moving the said tool into the opposite side of the die, and a snap-acting device for effecting withdrawal of said tool from the die after a predetermined advancing movement of the piercing punch into the die.

12. Forging apparatus comprising a blank-receiving die having openings in opposite sides thereof, a blank-engaging tool, a piercing punch, means for moving the piercing punch through the die, means for moving the said tool into the opposite side of the die, a snap-acting device for effecting withdrawal of said tool from the die after a predetermined advancing movement of the piercing punch into the die, and means controlled by the first-named advancing means for actuating said snap-acting device.

13. Forging apparatus comprising a blank-receiving die having openings in opposite sides thereof, a blank-engaging tool at one side of the die, a piercing punch at the other side of the die, in axial alignment with said tool, means for moving said piercing punch through the die, and a snap-acting device actuated in timed relation to the advancing movement of said piercing punch for permitting withdrawal of said blank-engaging tool from its blank-engaging position.

14. Forging apparatus comprising a crank shaft, a cam shaft, means for rotating said shafts

in synchronism, a blank-receiving die disposed intermediate said shafts, a piercing punch operatively connected to said cam shaft, for movement into the die, a slide operatively connected to the crank shaft and reciprocable thereby toward and from the die, a blank-engaging tool carried by said slide, a toggle device disposed between said tool and said slide, and normally set to project said tool forwardly of the slide, a tripping device in the path of travel of said slide, a cam on said cam shaft, and means actuated by said cam for operating said tripping device.

15. Forging apparatus comprising a crank shaft, a cam shaft, means for rotating said shafts in synchronism, a blank-receiving die disposed intermediate said shafts, a piercing punch operatively connected to said cam shaft, for movement into the die, a slide operatively connected to the crank shaft and reciprocable thereby toward and from the die, a blank-engaging tool carried by said slide, a toggle device disposed between said tool and said slide, and normally set to project said tool forwardly of the slide, a plate interposed between the said toggle device and the rear end of said tool, a tripping device in the path of travel of said slide, a cam on said cam shaft, and means actuated by said cam for operating said tripping device.

16. Forging apparatus comprising a crank shaft, a cam shaft, means for rotating said shafts in synchronism, a blank-receiving die disposed intermediate said shafts, a piercing punch operatively connected to said cam shaft, for movement into the die, a slide operatively connected to the crank shaft and reciprocable thereby toward and from the die, a blank-engaging tool carried by said slide, a toggle device disposed between said tool and said slide, and normally set to project said tool forwardly of the slide, a tripping device in the path of travel of said slide, a cam on said cam shaft, and means actuated by said cam for operating said tripping device, said cam actuated means being adjustable for operating said tripping device at a predetermined point in the advancing movement of said slide and said piercing punch.

17. Forging apparatus comprising a blank-receiving die having openings in opposite sides thereof, a blank-engaging tool movable into position to close one side of the die, a pin slidably mounted in said tool, a tubular crowning tool movable into the other side of the die, a piercing punch in the crowning tool disposed in axial alignment with the said pin, means for advancing the piercing punch beyond the end of the crowning tool, means for holding said pin in an advanced position during advancing movement of the crowning tool, and a device for releasing the pin during advancing movement of the punch, to permit retraction of the pin into said blank-engaging tool.

CHARLES FASSINGER.
